CLAIM

The ornamental design for a display assembly as shown and described.

DESCRIPTION

FIG. 1 is a front view showing a display assembly according to our new design;

FIG. 2 is a rear view thereof;

FIG. 3 is a right side view thereof;

FIG. 4 is a left side view thereof;

FIG. 5 is a bottom plan view thereof;

FIG. 6 is a top plan view thereof; and,

FIG. 7 is a front perspective view thereof.

The broken lines show portions of the display assembly that form no part of the claimed design.

1 Claim, 6 Drawing Sheets
